STITCH REGULATOR PLATE

Phillip S. Morse, Bronx, N. Y.

Application July 18, 1955, Serial No. 37,005

Term of patent 14 years

(Cl. D70—2)

FIG. 1

FIG. 2

Fig. 1 is a plan view of a stitch regulator plate showing my new design; and

Fig. 2 is an end view partially broken away.

The dominant features of my design reside in the portion shown in full lines.

I claim:

The ornamental design for a stitch regulator plate, substantially as shown and described.
